COMBINED FISHING ROD HANDLE AND REEL MOUNT

Walter L. Rives, Jacksonville, Fla.

Application March 26, 1948, Serial No. 145,367

Term of patent 14 years

(Cl. D31—4)

To all whom it may concern:

Be it known that I, Walter L. Rives, a citizen of the United States of America, residing at Jacksonville, county of Duval, and State of Florida, have invented a new, original, and ornamental Design for a Combined Fishing Rod Handle and Reel Mount, of which the following is a specification, reference being had to the accompanying drawing, forming a part thereof.

Figure 1 is a side elevation of the combined reel mount and handle;

Figure 2 is a view similar to Figure 1, showing the other side of the reel mount and handle;

Figure 3 is a perspective view of the reel mount and handle; and

Figure 4 is a front elevational view.

I claim:

The ornamental design for a combined fishing rod handle and reel mount, as shown.

WALTER L. RIVES.
